SIGNORS OF ONE-THIRD TO LOUIS WALDO THOMPSON, OF BELOIT, WISCONSIN.

PROCESS FOR PRODUCING GRINDING-DISKS.

945,931.

Specification of Letters Patent. Patented Jan. 11, 1910.

Application filed April 25, 1908. Serial No. 429,131.

To all whom it may concern:

Be it known that we, FREDERICK N. GARDNER and FREDERIC E. GARDNER, citizens of the United States, residing at Beloit, in the county of Rock and State of Wisconsin, have invented certain new and useful Improvements in Processes for Producing Grinding-Disks, of which the following is a specification.

10 This invention relates to processes for producing abrasive disks adapted to be secured to the rotary disk or disks of disk grinders. Heretofore such abrasive disks have been made by placing liquid glue upon 15 cloth, paper, or similar backing material, and sprinkling or spreading granular abrasive material, such as emery or corundum, upon the glue, the abrasive material becoming fixed to the backing sheet when the glue 20 hardened. In carrying out this process, the amount of abrasive material that can be attached to the sheet is limited by the amount of liquid glue that can be made to stand upon the sheet. Furthermore, the abrasive 25 material does not settle and mix evenly throughout the glue upon which it is deposited; consequently, as heretofore made, such grinding disks are more "free cutting" and softer on the surface than they are after 30 they have been used for a short time. As they wear down they cut less and less freely because the proportion of glue to abrasive material is excessive in the lower part of the layer of abrasive material. These consider- 35 ations render impracticable the manufacture by former methods of grinding disks much thicker than one and one-half or, at most, double the size of the grains of the abrasive material; for example, with No. 40 24 grain, the disk cannot be made over one-sixteenth of an inch to one-twelfth of an inch in thickness.

Our improved process may compose the following steps in thoroughly mixing a 45 binding material and a granular abrasive material in proper proportions to produce a grinding disk of the required temper; spreading said mixture upon a sheet of cloth, paper, or other suitable backing mate- 50 rial, which has been coated with just enough glue to cause the mixture to adhere firmly to the sheet; rolling the mixture into a layer of uniform thickness; tilting into cutting position the grains that were caused by the 55 rolling operation to lie with their faces

parallel to the face of the disk; and allowing the whole to dry and harden. It is evident that the thickness of the layer of abrasive material is limited only by the strength of the cement by means of which 60 said layer and the backing sheet are united.

In the accompanying drawings, Figure 1 is a sectional view of a machine that may be used in carrying out the process herein described. Fig. 2 is a view, partly in section, 65 of a roll that is useful in performing one step of the process. Fig. 3 is a fragmental sectional view of a grinding disk produced by our process.

In Fig. 1, 1 refers to a bench or table, and 70 2 to a mold mounted on said table, the diameter of the mold corresponding to the diameter of the disk grinder disk 3 to be made. Such disks ordinarily have a central opening 4 (Fig. 3), to define which a circular 75 block 5 is fixed in the center of the mold 2. 6 is a movable or false bottom in the mold, to support the disk during the process of manufacture. The bottom 6 is movable to remove the grinding disk from the mold, by 80 means of a spindle 7 slidably mounted in bearings 8 in a bracket 9 located beneath the bench or table 1, said spindle bearing at its upper end a crosshead 10 which is connected with the mold-bottom 6 by the pins 11, said pins being slidable within openings 12 in the table and the mold. A hand-wheel 13 has a screw-thread connection with the spindle 7 and bears against one of the bearings 8 of the bracket 9. A pivot 14 is arranged 90 centrally of the mold and provides means for pivotally mounting rollers for treating the surface of the grinding disk. 15 is a member having a hub 16 which is rotatably mounted upon the pivot 14, said member 95 having a shaft 17 fixed therein and carrying at its outer end a handle 18. 19 is a smooth roll and 20 a toothed roll which may be mounted upon the shaft 17.

In carrying out our process, we prefer- 100 ably cut the cloth, paper, or other backing material into the form of a disk or ring 21 of the desired size. The disk 21 is then placed in the mold 2, and its upper surface given a very thin coat of cement 22. A 105 granular abrasive material and a bonding material having been thoroughly mixed in the proper proportions to produce a grinding disk of the required temper, a sufficient quantity of the mixture to fill the mold is 110

placed in said mold, and the mixture may be rolled with the roll 19 into a layer 23 of uniform thickness. This rolling compresses the mixture somewhat and presses it into close contact with the film 22 of cement upon the backing sheet 21. Incidentally this rolling arranges substantially all of the grains at the surface of the layer of abrasive material with a flat surface parallel to the face of the disk, which obviously is not the most efficient cutting position of the grains. We therefore tilt the grains in any suitable way after they have been rolled into a flat layer so as to dispose their cutting edges toward the face of the disk, as indicated in Fig. 3. The tilting of the grains may be accomplished by means of the roll 20, said roll being substituted for the smooth roll 19 upon the shaft 17. After the grains have been tilted the member 15 is lifted off the pivot 14 and laid aside, and the hand-wheel 13 rotated to raise the grinding disk out of the mold 2. Said grinding disk is then removed and dried in any suitable way.

The bond being mixed with the abrasive material before the latter is placed upon the backing sheet, it is apparent that disks of much greater thickness than those heretofore produced can be made, and therefore that the life of our grinding disk is proportionately longer. Furthermore, our disk is of even cutting quality from the time its use is begun until the abrasive material has been worn away, as the bond is uniformly distributed throughout the layer of abrasive.

Our improved process also permits of obtaining any desired variations in the proportion of bond to abrasive material, with consequent variations in temper or cutting

quality, a result not readily and certainly obtainable by the processes heretofore employed.

It will be observed that a disk made in accordance with our invention requires no cutting or trimming.

Tilting the grains of abrasive material places the great majority of them in position to do effective work.

We claim as our invention:

1. The process of producing grinding disks for facing the sides of the disks of disk grinders, which consists in thoroughly mixing a bond and a granular abrasive material, applying a thin coat of cement to a backing sheet, placing said mixture upon the coated surface of said backing sheet, placing the grains with their cutting edges in cutting position, and drying.

2. The process of producing grinding disks for facing the sides of the disks of disk grinders, which consists in mixing a bond and a granular abrasive material, applying a thin coat of cement to a backing sheet, placing said mixture upon the coated surface of said backing sheet, rolling the mixture into a layer of uniform thickness, tilting the grains to dispose their cutting edges in cutting position, and drying.

3. The step in the process of producing grinding disks for facing the sides of the disks of disk grinders, which consists in tilting the grains after they have been deposited, so that their cutting edges are directed toward the face of the disk.

Corrections in Letters Patent No. 945,931.

It is hereby certified that in Letters Patent No. 945,931, granted January 11, 1910, upon the application of Frederick N. Gardner and Frederic E. Gardner, of Beloit, Wisconsin, for an improvement in "Processes for Producing Grinding-Disks" errors appear in the printed specification requiring correction as follows: Page 1, line 43, for the word "compose," read *comprise*; same page, line 44, the word "in" should be canceled; and that the said Letters Patent should be read with these corrections therein that the same may conform to the record of the case in the Patent Office.

Signed and sealed this 31st day of March, A. D., 1914.
